[57] CLAIM

The ornamental design for a cocktail table or the like, substantially as shown and described.

DESCRIPTION

FIG. 1 is a perspective view of a cocktail table or the like showing my design;

FIG. 2 is a top plan view; and

FIG. 3 is a side elevational view thereof.

The two sides of the table not shown in their entirety in FIG. 1 are the same in appearance as the side disclosed in FIG. 3.

FIG. 1

FIG. 3
